UNITED STATES PATENT OFFICE

ANSLEY D. WHITE, OF BUFFALO, NEW YORK.

BIT-BRACE.

SPECIFICATION forming part of Letters Patent No. 378,274, dated February 21, 1888.

Application filed October 24, 1887. Serial No. 253,216. (No model.)

To all whom it may concern:

Be it known that I, ANSLEY D. WHITE, of the city of Buffalo, in the county of Erie and State of New York, have invented new and 5 useful Improvements in Bit-Braces, of which the following is a specification.

This invention relates to improvements in that class of bit-braces which are commonly known as "corner braces," and in which the 10 bit-socket is arranged at an angle to the crank and connected with the latter by a universal joint.

The object of my invention is to construct the universal joint in such manner that the 15 bit-socket and crank can be set at a greater angle to each other than by the ordinary universal joint, and also to provide a detachable connection between the bit-stock and the crank, so that the angular socket can be removed and 20 the brace be used as an ordinary brace by attaching a straight socket to the crank.

The invention consists of the improvements, 25 which will be hereinafter fully described, and pointed out in the claims.

In the accompanying drawings, Figure 1 is 30 an elevation of my improved brace. Fig. 2 is a front view thereof. Fig. 3 is a longitudinal sectional elevation of the lower portion of the brace on an enlarged scale. Fig. 4 is a fragmentary elevation showing an ordinary 35 straight bit-socket attached to the crank. Fig. 5 is an elevation of the lower end of the crank. Figs. 6, 7, and 8 are horizontal sections of the detachable connection between the crank and 40 bit-socket, showing different positions of the parts.

Like letters of reference refer to like parts in the several figures.

A represents the bit-socket, which may be 45 of any suitable construction, and which is secured to the lower end of a vertical shank or spindle, a. The latter turns in a bearing, b, formed at the lower end of an angular frame, C, which supports the movable parts of the 50 brace.

D is the crank, which is provided with a handle, d, and at its outer end with a head, d', in the usual manner. The inner end of the 55 crank is detachably secured to a sleeve, E, which turns in a bearing, e, formed at the upper end of the angular supporting-frame C.

F represents the universal joint which con-

ncts the sleeve E with the shank a of the bit-socket and whereby the rotary motion of the crank is imparted to the bit-socket. The crank 55 D is provided at its inner end with a longitudinal slot or recess, g, which engages over a transverse pin or bar, g', arranged in the bore of the sleeve E, near the upper end thereof.

g" represents transverse notches or recesses 60 formed at the inner end of the slot g, on opposite sides thereof and communicating therewith.

Upon turning the lower end of the crank in one or the other direction the pin g' engages 65 in the transverse recesses g" of the slot, as shown in Figs. 6 and 7, whereby the sleeve E is securely attached to the crank. Upon turning the crank so that the pin g' clears the recesses g", as shown in Fig. 8, the sleeve with 70 the frame C can be detached from the crank. The bit-socket A and its shank a are detachably connected in a similar manner, the bit-socket being provided near its upper end with 75 a pin, h, and the shank with a longitudinal slot, h', having transverse recesses, as represented in Fig. 3. By removing the frame C from the end of the crank and detaching the bit-socket from its shank, the bit-socket can be 80 attached to the crank, as shown in Fig. 4, in which case the bit-socket stands in line with the crank and the brace operates as an ordinary straight brace. This construction forms 85 a simple and inexpensive connection, which dispenses with the use of set-screws and other fastening devices and permits the parts to be easily and quickly interchanged to convert the brace from a corner brace to an ordinary brace, or vice versa. The universal joint F is composed of a ring or frame, i, which is pivoted 90

between two jaws, i', arranged at the upper end of the shank a, a ring or frame, j, which is pivoted between two similar jaws, j', arranged at the lower end of the sleeve E, and connecting-links k, pivoted at opposite ends 95 to the rings i, j. The jaws i', j' are formed on collars i", j", which are secured to the spindle a and sleeve E by pins or rivets j". The links k are connected between the rings by a cross-bar, k', and their pivots are arranged at right 100 angles to the pivots whereby the rings are attached to the jaws i', j'.

L represents a handle secured to the supporting-frame C, and whereby the brace is

steadied and guided when used as a corner brace. The handle L is arranged out of line with or a short distance in rear of the bearing b of the bit-socket, as shown in Figs. 1 and 3, 5 so that the hand of the operator will not come in contact with the wall or other object against which the bit-socket is placed.

By constructing the joint with the links k k the crank and bit-socket can be arranged at a 10 greater angle to each other than is possible when the rings are pivoted directly to each 15 other, thereby removing the inner end of the crank a sufficient distance from the handle L to leave ample space between the handle and 15 crank for the hand of the operator.

I claim as my invention—

1. The combination, with the bit-socket and a tubular supporting frame, C, provided with a movable sleeve, E, having a transverse pin 20 or bar, of a crank provided at its end with a longitudinal slot engaging over said pin, and a transverse notch or recess communicating with said slot and in which said pin engages by turning the parts upon each other, sub- 25 stantially as set forth.

2. The combination, with the tubular bit-socket A, provided in its bore with a trans- 30 verse pin, h, of the crank D, provided in its end with a longitudinal slot, g, having a trans- 35 verse recess, g^2 , substantially as set forth.

3. The combination, with the supporting- 35 frame C, of the bit-socket A and sleeve E, provided, respectively, with transverse pins h and g' , the shank a and crank D, provided, re- spectively, with longitudinal slots h' and g , having transverse recesses, and a universal joint connecting the sleeve E and shank a, sub- stantially as set forth.

4. The combination, with the bit-socket and its shank provided with jaws i' , and the crank 40 D, provided with a sleeve, E, having jaws j' , of the universal joint F, connecting said sleeve and shank, and composed of a ring or frame, i, pivoted to the jaws i' , a ring or frame, j, pivoted to the jaws j' , and connecting-links k, hav- 45 ing their pivots arranged at right angles to the pivots of the rings, substantially as set forth.

5. The combination, with the bit-socket A, provided in its bore with a transverse pin, h, 50 and the crank D, provided at its end with a longitudinal slot, g, of an angular detachable frame, C, provided at one end with a movable sleeve, E, having a transverse pin, g' , adapted to engage with the slot g of the crank, and at 55 its opposite end with a shank, a, having a longitudinal slot, h' , adapted to engage with the pin h of the bit-socket, a universal joint, F, connecting the inner ends of the shank a and sleeve E, and a handle, L, secured to the frame C, 60 substantially as set forth.

6. The combination, with the bit-socket A and crank D, of the detachable angular frame C, connecting the crank D and socket A, and provided with a handle, L, arranged in rear 65 of the vertical plane of the socket A, substan- tially as set forth.

Witness my hand this 4th day of October, 1887.

ANSLEY D. WHITE.
